UNITED STATES PATENT OFFICE.

ELMER D. CUMMINGS, OF WASHINGTON, DISTRICT OF COLUMBIA.

AMMUNITION-HOIST.

1,381,084.

Specification of Letters Patent.

Patented June 7, 1921.

Application filed August 31, 1920. Serial No. 407,266.

(FILED UNDER THE ACT OF MARCH 3, 1883, 22 STAT. L., 625.)

To all whom it may concern:

Be it known that I, ELMER D. CUMMINGS, a citizen of the United States, stationed at Washington, D. C., have invented an Improvement in Ammunition-Hoists, of which the following is a specification.

The invention described herein may be used by the Government, or any of its officers or employees in prosecution of work for the Government, or by any other person in the United States, without payment of any royalty thereon.

This invention relates to a hoisting device designed especially for hoisting bags of powder and the like and refers more specifically to a grip car and conveyer forming a part of such hoisting mechanism.

In hoisting bags of powder or the like, it is desirable that the conveyer be constructed to ascend with the bag and load automatically, dump the same and return. To avoid jars and shocks and consequent wear and tear on the structure the return of the conveyer should be controlled and not left entirely to the action of gravity.

These objects are efficiently accomplished by making use of the return flight of the conveying cable to return the grip car and conveyer, and in order that this result may be attained it is necessary to provide means for automatically releasing the connection of the car to the up flight of the cable and connecting the car to the down flight.

The main object of the present invention is the provision of a grip car which will automatically release from one cable and then automatically grip another.

The invention also contemplates generally, improving the construction and enhancing the utility of grip cars of this character.

With these and other objects in view, the invention consists in the combination and arrangement of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings; wherein:

Figure 1 is a fragmentary view partly in elevation and partly in longitudinal section of a conveyer;

Fig. 2 is a similar view of the lower end of said conveyer, a grip car constructed in accordance with the invention shown in place therein;

Fig. 3 is a plan view of the grip-car; 60

Fig. 4 is a front elevation of the same, parts being removed and the car body indicated in dotted lines;

Fig. 5 is a side elevation, partly in section on the line V—V of Fig. 3; and 65

Fig. 6 is a vertical longitudinal section of the grip car.

Referring to the drawings by numerals of reference:

The conveyer may be of any suitable construction but as herein shown, consists of a tubular member or chute, 10 the lower receiving end of which is normally closed by a hood, 11, which is suitably hinged to the tube 10. At the upper end of the conveyer is provided a receiving table, 12, which is provided for the reception of bags, 13, of powder or the like. A cable, 14, is trained under a grooved pulley, 15, located at the bottom of the tube or chute, 10, and also over 80 the grooved pulley 16, suitably journaled in the frame work at the upper end of the chute. The upper end of the cable is led about an idler, 17, and over a pulley or drum, 18, which is driven by means of a worm, 19, formed on the shaft of a motor, 20, or in any other suitable manner. From the foregoing it will be understood that the cable has an ascending and a descending flight. 90

Within the tube, 10, are mounted spaced apart rails, 21, which serve as a support for the grip car and conveyer and also additional rails 22, which are engaged by the wheels 24, journaled toward the rear 95 end of the conveyer, 23. The conveyer, 23, has lugs, 24', depending from its forward end and contacting the rails, 21, to slide thereon. Links, 25, connect the conveyer, 23, to the grip car, 26, which car forms the 100 main subject of this invention.

The body of the car, 26, may be of any suitable form and is preferably open at the top and forward end, and to the rear wall of the car is threaded or otherwise secured a cylinder, 27, which is adapted to receive a piston, 28, suitably mounted at the lower end of the chute, the structure acting as a dash-pot which absorbs the shock of the car upon its return to lowermost position. 110

A horizontally disposed shaft, 29, extends transversely of the car, 26, and is mounted in the side walls thereof. A trip arm 30, is pivotally mounted on the shaft, 29, adjacent one side of the car, and this arm is apertured between its ends to receive a pin 31, and is angularly disposed at its lower end, as indicated at 32, to form a projection which may be contacted for the purpose of rocking the arm. A link, 33, is mounted on the shaft, 29, adjacent the trip arm, 30, and the link is apertured in its lower end to receive the journaled pin, 31, and is formed with an outwardly projecting finger, 33', which acts as a stop to limit the throw of the link and trip-arm as will soon be apparent. A grip link 34, has its upper end bifurcated to straddle the lower end of the link, 33, and the prongs of said bifurcated portion are apertured to receive the journaling pin 31. To the lower end of the link, 34, is pivotally secured a grip-shoe, 35, which is formed to engage the up-flight of the cable, 14. The shoe, 35, is normally held in its rearmost position out of contact with the cable by any suitable means, such as the retractile spring, 36, one end of which is pivotally connected to the shoe and the other end of which engages the apertured lug, 37, projecting from the rear wall of the car, 26.

From the foregoing, and a consideration of Fig. 5, it will be evident that when the trip-arm, 30, is rocked forwardly the link, 33, because of its connection to the pin, 31, will likewise draw with it the grip link, 34, thereby drawing such link and the grip-shoe against the force of the spring, 36, and forcing the shoe into contact with the up cable, 14. This forward movement of the trip arm may be accomplished by any suitable means such as the lever, 32', (Fig. 2) which is suitably journaled at the lower end of the chute and is manually rocked to contact the projecting end, 32, of the trip-arm and rock the arm to forward or grip setting position.

The brake arm, 38, is connected to the shaft, 29, toward the other side of the car, 26, and this arm is formed with a tapped boss into which is threaded a rearwardly projecting arm, 39, upon which is mounted an adjustable weight, 40. The brake arm is formed with an upwardly projecting nose, 41, which is adapted to be contacted for the purpose of rocking the arm to release the brake as will be hereinafter set forth. The brake-shoe, 42, is pivotally connected to the lower end of the arm, 38, and is formed to engage the downward flight of the cable, 14. The brake-shoe is normally urged toward its cable engaging position by means of the weight, 40, and the retractile spring, 43, one end of which is pivotally connected to the shoe and the other end of which engages an eye formed in a band, 44, which en-

circles a shaft, 45, extending transversely of a car, 26, and supported in the walls thereof.

For the purpose of holding the brake-shoe from contact with the cable when the car is ascending and for moving it into contact with the cable when the car is descending, an eye, 46, is formed on the brake arm, 38, and projects rearwardly therefrom and to this eye is pivotally secured the upper end of a friction link, 47, to the lower end of which is pivoted a friction shoe, 48, adapted for sliding contact with a rail, 21. The friction link, 47, is likewise formed with a tapped boss into which is threaded the rearwardly extending arm, 49, upon which is mounted an adjustable weight, 50. From a consideration of the Figs. 3, 4 and 6, taken in conjunction with the foregoing description, it will be apparent that the rearward movement of the friction-shoe, 48, will rock the brake-arm, 38, on the shaft, 29, in a direction to raise the brake-shoe, 42, from engagement with the cable, 14. Slight movement of the shoe, 48, will rock the arm, 38, in direction to bring the brake-shoe into engagement with the cable, 14.

For the purpose of releasing the grip, 35, from the up flight of the cable, 14, when the car has reached its uppermost position and the conveyer has dumped its load of powder or the like upon the receiving table, an adjustable block, 51, is suitably mounted in the chute, 10, adjacent its upper end beside a rail, 21, the block being in position to contact the end, 32, of the trip arm, 30, and rock the arm to lift the grip-shoe, 35, from engagement with the cable. During the upward movement of the car the friction shoe, 48, being in contact with a rail, 21, will tend to move rearwardly and lift the brake-shoe, 42, from engagement with the cable, 14. When the grip is released, upon arrival of the car at its uppermost position, gravity will cause the car to start to descend. This downward movement of the car will urge the friction shoe, 48, forward and rock the brake-arm, 38, to set the brake-shoe, 42, in engagement with the down flight of the cable, 14, thus insuring a downward movement of the grip car in unison with the movement of the cable.

In order that the brake may be released from the cable when the grip car has reached its lowermost position, an adjustable striker, 52, is provided at the lower end of the chute and is positioned to engage the nose, 41, to rock the brake arm, 38, and release the brake shoe.

To compensate for the wear of the cable on the bottom of the grip car in its passage therethrough, wearing strips, 53, may be detachably secured in grooves formed in the bottom of the car, the said strips being in frictional contact with the flights of the cable.

From the foregoing, it will be apparent that the action of the car in releasing from the up cable and gripping the down cable is entirely automatic and lets the car return 5 to normaly or lowermost position without undue speed and consequent jar and shock to the mechanism.

As the operation of the device has been amply set forth, in the course of the 10 description a special and extended explanation will not be added.

Having described my invention, what I claim as new and desire to secure by Letters Patent, is:—

15 1. A hoist including an endless cable, a grip car, a grip for engagement with the cable, means operable to automatically release the grip, a brake, and means operable to engage the brake with the cable to move 20 the car in an opposite direction.

2. A hoist including an endless cable, a grip car, a grip carried by the car and operable to engage the cable to move the car in one direction, means operable to automatically 25 release the grip, a brake shoe, and means for operating the shoe to engage the cable and to move the car in an opposite direction.

3. A hoist including an endless traveler, 30 a grip car, a grip carried by the car and swingable into position to engage a flight of the traveler to move the car in one direction, a brake connected to the car and a friction member operating when the grip is released to bring the brake into engagement with the traveler to move the car in the opposite direction.

4. A hoist including a support, an endless traveler carried by the support, a grip car 40 mounted to travel on the support, a grip on the car and operable to engage the traveler to carry the car therewith in one direction, an element for operating the grip to engage and release the traveler, a brake connected 45 to the car and engageable with the traveler to move the car in an opposite direction, a friction member for throwing the brake into engagement with the traveler and means for automatically releasing the brake from the 50 traveler.

5. A hoist including a support, an endless traveler carried by the support, a grip car, a grip on the car and adapted to engage the carrier, a switch arm for throwing the grip, 55 means for moving the switch arm to force the grip into contact with the traveler to move the car in one direction, adjustable means carried by the support and engageable with the switch arm to automatically release the

grip when the car has reached its limit of 60 travel in said direction, a friction member moved with respect to the car by return movement of the car under the force of gravity, a brake shoe thrown into engagement with the traveler by the movement of 65 the friction member, and means connected to the support to automatically release the brake when the car has returned to its original or starting position.

6. A hoist including a tube, a traveler 70 connected to the tube, a grip car in the tube and moveable therein, a grip carried by the car and engageable with the traveler, means connected to the tube for moving the grip into engagement with the traveler, means 75 adjustably mounted in the tube for automatically releasing the grip from the traveler, a brake carried by the car, friction means contacting the tube and operating on return movement of the car to throw the brake into 80 engagement with the down flight of the traveler, and adjustable means for throwing the brake out of engagement with the traveler.

7. A hoist, including a tube, an endless 85 cable to travel in the tube, a grip car movable in the tube, a grip carried by the car and engageable with the cable, means connected to the tube and operable to throw the grip into engagement with the cable, a trip block 90 mounted for adjustment in the tube, and operating to release the grip, a brake shoe carried by the car and engageable with the down flight of the cable and friction means for operating the brake. 95

8. A grip car including a grip normally held in released position, means for throwing the grip to gripping or released position, a brake, and means operating upon movement of the car in one direction to move the 100 brake to operative position.

9. A grip car, including a frame, a grip journaled in the frame, a trip arm connected to the frame and operable to move the grip to gripping or released position, a brake 105 pivotally connected to the frame, and a friction member carried by the frame and operating upon movement of the car in one direction to apply the brake.

10. A grip car, including a frame, a shaft 110 carried by the frame, a grip connected to the shaft, a trip arm connected to the shaft and operable to move the grip to gripping and released positions, a brake connected to the shaft, and a friction member connected to 115 the shaft and operating upon movement of the car in one direction to actuate the brake.

ELMER D. CUMMINGS.
